UNITED STATES PATENT OFFICE.

ALBERT H. DE VOE, OF WESTFIELD, NEW JERSEY, ASSIGNOR TO THE SINGER
MANUFACTURING COMPANY, A CORPORATION OF NEW JERSEY.

DRIP-PAN FOR SEWING-MACHINES.

1,299,143.

Specification of Letters Patent.

Patented Apr. 1, 1919.

Application filed February 17, 1917. Serial No. 149,371.

To all whom it may concern:

Be it known that I, ALBERT H. DE VOE, a citizen of the United States, residing at Westfield, in the county of Union and State 5 of New Jersey, have invented certain new and useful Improvements in Drip-Pans for Sewing-Machines, of which the following is a specification, reference being had thereto in the accompanying drawings.

10 This invention relates to a power table for sewing machines and more particularly to a drip-pan support for machines having their main-shaft located between the throat-plate or work-supporting surface and a bed- 15 plate.

With the object of clearing the fabric-supporting surface on all sides of the needle so that an operator may handle fabric with great facility this invention provides for the 20 location of the throat-plate, cloth-plate and table-top in substantially the same plane. With the object of affording ready access to the lower thread-handling mechanism of a sewing machine as well as facilitating the 25 removal of such machine from the table when occasion demands, it provides for shifting the cloth-plate to expose the entire bed-plate of the machine. And with the object of preserving a sufficient mechanical ad- 30 vantage to enable an operator to manipulate a knee-shift device against the resistance offered by certain movable elements of a sewing machine, such as a presser-foot or multiple tension device, it provides a location and 35 arrangement of the knee-shift device above the bottom of the drip-pan.

To the attainment of these ends a power table is provided with a pair of brackets secured to opposite sides of the table at the 40 opposite ends of a recess provided in the table. A drip-pan is secured to the brackets by fastening-bolts which pass through vertically arranged slots that permit the drip-pan being adjusted to different elevations.

45 The drip-pan which is stiffened with suitably disposed ribs and provided with lugs for seating a sewing machine clear of the bottom of the pan, is preferably rectangular in shape resembling when viewed from 50 above an open box. A knee-shift lever is journaled in the sides of the drip-pan above its bottom and carries a pair of fingers for operatively controlling a lever pivoted to the rear side of the drip-pan. A pair of cover- 55 plates are provided for inclosing the lower

thread-handling mechanism. The rear cover-plate is removably fitted to the recess in the table and is cut away to conform to the outlines of the throat-plate and vertical standard of the machine. The front cover- 60 plate is provided with a depending apron filling the gap made by the recess in the front edge of the table-top and is supported on horizontal pivots formed by pinning together pairs of lugs extending forwardly 65 and rearwardly respectively from the front side of the drip-pan and apron. A spring is secured to the front side of the drip-pan adjacent one of the pairs of lugs and acts on the toe of a lug carried by the apron to yield- 70 ingly hold the front cover-plate in normal operative position.

The invention further consists in certain details of construction which will appear from the following description of the de- 75 vice shown in the drawings, in which Figure 1 is a perspective view of the drip-pan supported by the brackets secured to the table which is indicated by dotted lines. Fig. 2 is a longitudinal section in a vertical plane 80 passing through the line A—A' Fig. 1 and Fig. 3 is a transverse section taken in a vertical plane containing the line B—B', Fig. 1, with the front half section of the cloth-plate in normal position. 85

In a power-table bench 1 of any suitable material, preferably wood, a recess 2 is formed in any convenient way, a portion 3 extending from its front edge into proximity to its rear edge being left to preserve as 90 much as possible the desirable appearance of a wooden finish on the front edge of the table. A sewing machine 4, seated upon a drip-pan 5 supported below the table-top by brackets 6 and 7, is positioned within the re- 95 cess with its throat-plate 8 substantially in the plane of the table-top, and with its lower-thread handling mechanism 9 and bed-plate 10 entirely inclosed by a cloth-plate, comprising a rear half-section 11 removably seated on the edges of the recess 2 and a front half-section 12 having a depending apron 13 hinged to the drip-pan.

Pairs of spaced lugs 14 and 15 on the rear of the apron and front of the drip-pan, re- 105 spectively, are connected by horizontally ar- ranged pins 16 and afford means for mov- ing the front half-section from a position above the lower thread-handling mechanism to a position fully exposing the same for re- 110

pair and adjustment purposes, as shown clearly in Fig. 1, additional facility for these purposes being afforded by making the rear half-section bodily removable. A relatively 5 strong leaf spring 17 fixed by the screw 18 to the drip-pan is adapted to engage the toe 19 of one of the lugs 14 to hold the front half-section of the cloth-plate in normal operative position against the complementary 10 rear half-section. Both sections are cut away at 11' and 12', respectively, as indicated in Fig. 1 to embrace the vertical standard 4' and the rear section is also incised at 11" to embrace the throat-plate 8 with which 15 it is flush.

The drip-pan 5, which is suitably stiffened with ribs 5' and provided with tapped lugs 5" sustaining the bed-plate clear of the bottom of the pan, as previously mentioned is 20 supported from the brackets 6 and 7.

Bracket 6 at the left end of the recess comprises a horizontal portion 20 drilled as shown for wood-screws holding it to the bottom of the table-top, and vertically disposed 25 flanges 21 and 22 (Fig. 1) provided with apertures 28 for the fastening-bolts 23 threaded into the drip-pan, said flanges being at right angles to each other and located substantially in parallelism to the end and 30 rear side walls of the recess in the table.

The bracket 7 at the other end of the recess is U-shaped and is located with its horizontal extension 24 resting on the end and side walls of the recess so as to reinforce the 35 wood at this point as well as distribute over a relatively large area of the wood the weight of the parts and the strain from the driving belt which is adapted to pass through the slot 5''' over the pulley 4''. Vertical flanges 40 25 of the bracket 7 are adapted to receive fastening-bolts 26 passing through apertures 27 in the drip-pan. The several apertures 27 and 28 are elongated vertically to provide an adjustment which admits of accurately 45 locating the drip-pan and nicely setting the throat-plate of the machine flush with the table-top to compensate for slight differences in either the sewing machine or drip-pan.

Viewed as in Fig. 1, the drip-pan resembles an open box. It is preferably of rectangular shape with low sides and ends. Journaled in its sides and extending across and above the bed-plate of the machine is a rock-shaft 30 from which at its forward end depends an arm 31 in convenient reach of an operator's knee. At its rear end the shaft is provided with a finger 32 for lifting one end of a lever 33 pivoted at 34 to the rear 55 side of the drip-pan and adapted to be connected at its other end by a reach rod 35 or other suitable means to one or more movable elements of the sewing machine, such as a presser-foot lifting lever or multiple tension device, not shown. The rock-shaft at its 60

rear end also carries a second finger 36 which is shaped to engage the edge of the rear side of the drip-pan and limit the movement of the rock-shaft in a direction opposite to that in which it is turned when actuated by 70 the operator. The fingers mentioned may be formed upon the shaft in any suitable manner but preferably as shown they are made integral with a disk 37 secured by a set screw 38 to the shaft.

The horizontal extension 24 of the bracket 7 is provided with an apertured boss 24' to which is adapted to be secured a combined tape-reel and multiple cop-arm, which are not shown in the drawings as they are to be 80 made the subject matter of another application.

Having thus set forth the nature of the invention, what I claim herein is:—

1. In a power-table of the class described, 85 in combination, a sewing machine having a bed-plate and a superimposed cloth-plate, means on which the machine is seated and by which it is supported with its bed-plate below the top of the table, and adjustable 90 connections permitting bodily displacement of said means in order to level the cloth-plate flush with the table.

2. In a power-table of the class described 95 provided with a recess, the combination with a sewing machine having a throat-plate, of a drip-pan for supporting the machine within the recess in the table, and brackets fixed to the table and adjustably connected to said drip-pan for permitting the throat-plate of 100 the sewing machine to be located substantially in the plane of the table-top.

3. In a power-table of the class described, 105 in combination, a sewing machine, a supporting pan, means for sustaining said supporting pan in position below the plane of the table-top including a pair of brackets arranged at opposite ends of the pan and supported from opposite sides of the table-top.

4. In a power-table of the class described 110 provided with a recess, in combination, a drip-pan, a sewing machine having a throat-plate and suitable upper and lower stitch-forming instrumentalities, said sewing machine being supported on said drip-pan within said recess, a cloth-plate comprising sections substantially flush with the throat-plate when in normal position, said sections being movable to expose the entire lower 115 stitch-forming instrumentalities, whereby accessibility for repair or adjustment is afforded.

5. In a power-table of the class described 120 provided with a recess extending from the front edge of the table into proximity to its back edge, in combination, a drip-pan, a sewing machine having a throat-plate and supported on said drip-pan within said recess in the table-top, a cloth-plate comprising 125

ing sections substantially flush with the throat-plate, one of said sections being movably supported on the drip-pan and having a depending apron arranged and located to close the gap made by the recess in the front edge of the table when in normal position.

6. In a power-table of the class described provided with a recess, in combination, a drip-pan, a sewing machine having a throat-plate and suitable upper and lower stitch-forming instrumentalities, said sewing machine being supported on said drip-pan within said recess, a cloth-plate comprising front and rear sections shaped to embrace the throat-plate and inclose the stitch-forming instrumentalities, said front section being supported by the drip-pan on horizontally arranged pivots whereby it may be readily swung to expose all the lower stitch-forming instrumentalities.

7. In a power-table of the class described provided with a recess, in combination, a drip-pan, a sewing machine having a bed-plate, said bed-plate being seated upon said drip-pan within said recess, a rock-shaft extending across the drip-pan above the bed-plate of the machine, a knee-shift depending from the forward end of said rock-shaft, an

arm on the rear end of said rock-shaft, a lever pivoted to said drip-pan in juxtaposition to said arm and adapted to be connected with a movable element of the sewing machine, whereby force applied to the knee-shift will actuate the lever pivoted to the drip-pan.

8. In a power-table of the class described provided with a recess, in combination, a drip-pan, a sewing machine having a bed-plate, said bed-plate being seated upon said drip-pan within said recess, a rock-shaft extending across the drip-pan above the bed-plate of the machine, a knee shift depending from the forward end of said rock-shaft, an arm on the rear end of said rock-shaft, a lever pivoted to said drip-pan in juxtaposition to said arm and adapted to be connected with a movable element of the sewing machine, whereby force applied to the knee shift will actuate the lever pivoted to the drip-pan, and means carried by the rock-shaft and coöperating with the drip-pan to limit the rotation of the rock-shaft in one direction.

In testimony whereof, I have signed my name to this specification.

ALBERT H. DE VOE.
